BATHTUB SEAT ATTACHMENT

George B. Bentz, New York, N. Y.

Application September 14, 1937, Serial No. 163,846

3 Claims. (Cl. 4—185)

The invention aims to provide a new and improved attachment affording a convenient seat for a bathtub, the construction being exceptionally simple and inexpensive, easy to apply and remove, and of such form that it will tightly wedge into place.

Another object of the invention is to provide a novel means for varying the length of the seat attachment to not only fit tubs of different widths, 10 but to enable the attachment to be supported relatively high or comparatively low in a tub of one width, according to the user's desires.

With the foregoing in view, the invention resides in the novel subject matter hereinafter described and claimed, description being accomplished by reference to the accompanying drawings.

Fig. 1 is a transverse sectional view through a bathtub showing an edge view of one form of the 20 invention.

Fig. 2 is a perspective view of the seat attachment shown in Fig. 1.

Fig. 3 is a perspective view showing a slightly different form of seat attachment.

In Figs. 1 and 2, a one-piece elongated seat 10 is provided, the ends of said seat being provided with substantially vertical end plates 11 which are rigidly attached thereto by any suitable means, providing substantially a one-piece structure. The end plates 11 extend both upwardly and downwardly from the seat 10 and they converge downwardly to abut the inner sides of the side walls 12 of a bathtub. If desired, the outer sides of the plates 11 may be provided with a yieldable covering 13 of rubber or the like to prevent marring the finish of the tub, but even if these coverings be omitted, the attachment will wedge tightly into place and cannot slip.

In Fig. 3, an elongated seat 14 is provided hav-

ing downwardly turned integral end plates 15 at its ends to perform the same function as the end plates 11. The outer sides of these end plates 15 are preferably provided with coverings 16 of rubber or the like.

By providing the novel construction shown and described or a substantial equivalent thereof, a simple and advantageous seat attachment is provided, and one which may be readily applied and removed.

While the details disclosed are preferred, minor variations may of course be made within the scope of the invention as claimed.

I claim:

1. A bathtub attachment comprising an elongated seat provided at its ends with rigidly attached inherently rigid end plates which project vertically in at least one direction from said seat, said end plates being disposed in downwardly converging planes to abut the inner sides of the side walls of a bathtub and wedge tightly against the same.

2. A bathtub attachment comprising an elongated seat provided at its ends with rigidly attached inherently rigid end plates which project both upwardly and downwardly from said seat, said end plates being disposed in downwardly converging planes to abut the inner sides of the side walls of a bathtub and wedge tightly against the same.

3. A bathtub attachment comprising an elongated seat provided at its ends with rigidly attached inherently rigid end plates which project downwardly but not upwardly from the ends of said seat, said end plates being disposed in downwardly converging planes to abut the inner sides of the side walls of a bathtub and wedge tightly against the same.

GEORGE B. BENTZ.
